UNITED STATES PATENT OFFICE.

HOMER P. CURTIS, OF DENVER, COLORADO, ASSIGNOR OF ONE-HALF TO THE PLAINS IRON WORKS COMPANY, OF DENVER, COLORADO, A CORPORATION OF COLORADO.

PIPE-BENDING MACHINE.

1,401,394.

Specification of Letters Patent. Patented Dec. 27, 1921.

Application filed August 17, 1920. Serial No. 404,152.

To all whom it may concern:

Be it known that I, HOMER P. CURTIS, a citizen of the United States of America, residing at the city and county of Denver 5 and State of Colorado, have invented a new and useful Pipe-Bending Machine, of which the following is a specification.

My invention relates to a new and improved pipe bending machine, and the 10 objects of my invention are:

First: to provide a pipe bending machine that is adapted to receive lengths of pipe and bend them into any desired part of full circular coils.

15 Second: to provide a machine which is especially adapted to bend large iron or steel or copper pipes in either portion or parts of full coils or into full coils, either at the ends of lengths of pipes or at any part of their 20 lengths. And

Third: to provide a powerful and easily manipulated pipe bending machine on which pipe can be quickly placed and bent and removed therefrom by any one or two mechanics.

25 I attain these objects by the mechanism illustrated in the accompanying drawings, in which:

Figure 1 is a side elevation of the improved pipe bending machine, a section of pipe being supported thereby in position for bending.

Fig. 2 is a plan view thereof.

Fig. 3 is a transverse, vertical, sectional 35 view of the same on the line 3—3 of Fig. 2.

Fig. 4 is a fragmental sectional view showing the manner of securing the end of a pipe to the revoluble former, and also the mandrel, which is supported in the pipe to prevent buckling or crumpling of the pipe at the 40 bending point and for a distance back of that point.

Fig. 5 is a fragmental plan view, illustrating the manner of clamping a long section 45 of pipe when the same is to be bent intermediate of its ends.

Fig. 6 is an end view of Fig. 5.

Fig. 7 is a side view illustrating a modification in the pipe end clamping means.

50 Figs. 8 and 9 illustrate half round U-shaped pipe bends, respectively.

Fig. 10 is a sectional view of the former and its driven pipe abutment roller, showing the circumferential gear tooth meshing pitch 55 line of the semi-circular gear of the former

extending beyond the center of the curved pipe gripping grooves of the former and its drum roller, in order to make the driven roller move a trifle faster at its peripheral pipe engaging point than the turning speed 60 of the pipe engaging groove of the former.

Fig. 11 illustrates a perspective view of the plug that clamps the pipe to the pipe bending former. And

Fig. 12 illustrates one manner of connecting the ends of pipe sections together.

Similar reference numerals refer to similar parts throughout the several views.

Referring to the drawings:

The numeral 1, designates the bed plate, or 70 table of my improved pipe bending machine, which is provided with supporting legs 2, and with brackets 3, which are secured at their outer ends to the underside of the front portion of the bed plate and depend therefrom, and their inner ends are integrally connected to form a journal box 4, in which the lower end of a vertical shaft 5, is rotatably journaled. On the upper end of the shaft 5, is rigidly secured a gear wheel, 80 preferably a worm gear 8, which is securely bolted to a revoluble circular table 6, which fits loosely in a circular opening in the table 1, its upper surface being flush with the upper surface of the table.

Upon the circular table is securely bolted a semi-circular casting 7, which constitutes a pipe bending former, as will presently be shown.

The worm gear 8, meshes with a worm 90 pinion 8^A, on a shaft 9, which is mounted in bearings 9^A, secured to the underside of the table. The shaft 9, is also provided with a belt receiving cone pulley 10, by which rotating power is connected to it and its shaft 95 and to the worm pinion, and the worm gear, and consequently the vertical shaft 5, and to the circular table 6, to which several speeds can be given by the different step pulley portions on its cone 10.

100 The bed plate is provided with two extension portions 11 and 12. The extension portion 11, is provided with two pairs of T-shaped slots 13 and 14, which are positioned at a few feet apart, and to each of these two pairs of T slots, blocks 15 and 16, are slidably mounted, and they are secured adjustably in set positions to these slots by the bolts 17. These brackets support guide rollers 18 and 19, on shafts 18^A, and 19^A, that 110

are secured vertically in the opposite ends 19^B, of these blocks that are formed on the opposite sides of a recess 19^C, that is formed in the inner ends of the brackets. These 5 rollers 18 and 19, are arranged to act as guides and abutments to the pipes when bending them, as will be fully described hereinafter.

The bed plate extension 12, extends far 10 enough away from the guide roller 18, to receive on it, between the guide roller 18 and its outer end plate 20, the longest lengths 15 of pipes or of tubes or of casings 21.

And my invention contemplates a pipe 20 bending machine that is adapted to bend pipes made of either wrought iron, steel, copper, or of any other malleable metal, from the smallest sizes up to the largest sizes that it is practical to bend and to use 25 in tanks or for any construction work, requiring either straight or spirally coiled pipes.

The extension 12, of the bed plate or table 30 is also provided with legs 2, and adjacent 25 its outer end, it is provided with parallel T slots 12^A, in which are slidably mounted the headed ends of bolts 22, upon which is secured a bracket 20, by clamping nuts, as shown. The upright portion of the bracket 35 20, is provided with a hole through which the threaded end of a rod 23, passes, and receives a nut 23^A.

The opposite end of this rod 23, extends to 40 and is threaded into one end of a mandrel 35 24, which may be of any predetermined length, but which I preferably make about ten times the diameter of the pipe to be bent. This mandrel is made to fit loosely but 45 snugly into the pipe being bent. The opposite end 25, of the mandrel, for a short 50 distance of about one-half of the diameter of the pipe is tapered smaller in diameter than the full diameter of the body portion of the mandrel, and its extreme terminal end 55 is rounded enough to allow it to be easily inserted into and pushed through the pipe 60 that is placed on the extension portion of the bed plate to be bent until its tapering end portion projects a short distance beyond 65 the inner end of the pipe, as will be fully described hereinafter.

The former 7, is preferably of semi-circular shape, and as it is secured to the top 55 of the table, it is rotatively turned by and with the shaft and table. The outer peripheral edge of the pipe former is machine finished concentric to the vertical axis of the shaft 5, and the face of its peripheral edge is divided into a bottom stepped top rim portion 27, also into a central semi-circular concaved groove recess portion 28, and also 60 into a gear tooth portion 29. The bottom rim portion 27, rests on the top surface of the table, and its stepped shouldered portion 65 30, fits over a projecting lip 31, that is

formed on the bottom portion of the guide roller 18, which is provided with a stepped portion 32, of the same size as the former, so that the lower portions of the pipe curving former and of the guide roller intersect and intermeshingly contact with each other as they rotate with a pipe between them. The two opposing pipes receiving and fitting semi-circular grooves fitting tightly 70 around the circumference of the pipe, being 75 bent as will be fully explained hereinafter.

The gear teeth of the upper portion of the rim of the pipe former 7, meshes with a circumferential row of similar teeth that are formed on the upper edge of the face of the 80 guide roller 18, which thus becomes a driven roller, and the face of this driven guide roller is provided with a semi-circular recess curve 33, that is positioned directly opposite to the pipe curve in the face of the pipe former 85 7, and these recess curves in the faces of the pipe former and in the driven roller 18, must fit closely around the circumference of the pipe that is being bent; consequently, when pipes of different sizes are to be bent, 90 pipe curving formers 7, and driven rollers 18, of different sizes made to fit tightly around the pipes must be provided and mounted on the table and in the brackets 15 and 16; and it is for this purpose that the 95 driven roller 18, is slidably mounted in its supporting extension portion of the bed plates.

The idler roller 19, also is provided with a recess groove 34, that fits half way around 100 the size of pipes that are being bent. This roller acts as a rolling abutment to the side pressure of the pipes, which have a tendency to swing away from the direction in which the pipes are being bent, and consequently this idler roller 19, is adjustably placed and slidably mounted so that it can be moved to bear against pipes of all sizes so that it can receive this side pressure.

In assembling the pipe curving former 110 7, and the driven roller 18, into pipe bending relation with each other on the bed plate of my pipe bending machine, it is necessary that they be so positioned that a line A, drawn through their axial vertical centers, 115 be a diametrically radial line through the diametrical center and axis of the table and also of the driven roller, and that the center of the extension 12, be a tangential line B; also that the pipes will be drawn straight 120 through and between the axial center of the two oppositely pipe receiving grooves in the former and in the driven roller, and they will bear against the abutment roller 19. Then the pipe will be pinched tightly 125 between the former and this driven roller; consequently also through the center of straight lengths of pipe laid on the longitudinal center of the extension 12 and the bed plate; and it is also necessary, when 130

starting to bend a pipe, that the pipe be placed on the extension 12, and that the mandrel be inserted in its rear end and be pushed through it until its forward rounded end comes to the radial and diametrical center line A, in which position the mandrel is set and fixed by adjustably turning the nut on the end of the rod 23, against the back of the end plate 20 of the extension 12. The mandrel is inserted in the pipe at this point until its full diameter is even with the line A. The immediate end of the mandrel is rounded, and this rounded portion would naturally be a little smaller in diameter than the full body of the mandrel and would project slightly beyond the point where the full diameter of the mandrel should be placed directly on this diametrically and radial line A, as this is the point where the pipes start to bend when the curving action of the segment shaped former moves to curve it in either a partial or a semi-circular or a full circular curve.

When about to bend a pipe, the forward swinging end 26, of the pipe curving former 7, starts to bend the pipe, with the center of the first two or three or four teeth, preferably three teeth, of its forwardly swinging end 26, in mesh with the teeth of the driven roller, and with its front edge portion through the center of the first three teeth on the diametrical center line A through the pipe former 7, and the axis of the driven roller 18, and of the rotating table.

After the former has been placed in the position described, the pipe is then pushed a little beyond the end of the mandrel in order that it may be secured to the forwardly swinging end of the pipe curving former, which is necessary as the end of the pipe, or at least that portion of the pipe where the curving bend is to start, has to be secured tightly and rigidly to the forwardly swinging and moving end of the former.

My invention contemplates any means of securing the end of the pipes that are to be bent, to the pipe former 7, which, as it swings around with the rotating movement of the table, must carry the pipe clamped tightly at its end to it, and around with it in order to bend it. I preferably, however, carry out this feature of my invention in the following manner:

On the forwardly swinging movement end of the pipe curving former, I cast a lug 26, and in the end of the pipe 21, that is to be bent, I insert a short plug 27^B, which fits snugly therein and is provided with sharp edged circular bands 27^A, that are beveled to permit their sharp edges to cut into the inner surface of the pipe and grip it, as will be presently explained. This plug 27^B, is provided with a head portion 28^D, extend-

ing in a radial direction toward the former; the plug 27^B, is also provided with a lug 28^A, that projects at right angles from the head piece 28^D, and extends alongside of the pipe 21, and overlaps loosely the lug 26, on the former, and a set screw 28^B, is threaded through the lug of the plug to bear against the lug 26, of the former, and thus clamp the plug and the end of the pipe 21, to the former. This plug, with its head and lug portions, forms a U-shaped coupling for connecting the end of the pipe that is to be bent, to the former, and when the former starts to turning, it pushes against the set screw, and consequently the plug and the sharp edges of the bands on the plug are drawn tightly against the inner surface of the pipe by the set screw 28^B. Consequently when the former starts to turning, its lug pushes against the set screw and the plug and the sharp edged bands on the plug dig into it and tightly grip it and force it to move with the former without slipping movement between them. When, however, a semi-circular curve is to be formed in the center or in a part of the length of a pipe, as indicated in Fig. 5, a yoke-shaped clamp 29^A, is employed, which is placed over the pipe, as shown, its ends, which are threaded, extending through holes in the lug 26. These threaded ends of the clamp receive clamp nuts 30^A, which, when tightly screwed against the lug 26, cause the clamp 29^A, to rigidly secure the pipe to the former 7. A block 28^C, may be inserted in the pipe to the point where the clamp 29^A, engages the pipe, to prevent the pipe from being indented by the clamp.

In making a half round bend, however, the pipe is positioned on the mandrel and between the semi-circular grooved recesses of the pipe bending former and its opposing driven roller 18, so that the plug 27^B, can be inserted in the pipe and the screw tightened, then the plug and the pipe are clamped tightly together to the lug of the pipe bending and curving former. It is only then necessary to move the idler roller 19, against the pipe, and the machine and the pipe are ready to be started and the pipe curved and bent as desired. The operation of bending or curving pipes into quarter circles or half or semi-circles or full circles, being as follows:

Having set the mandrel with the pipe on it in the semi-circular grooves between the former and its driven roller and securely clamped to the former, the pipe is supported on its inside by the mandrel, and it is held tightly in the semi-circular grooves of the former and its driven roller; consequently, it cannot be flattened or dented as it is drawn around the former. Rotative power is then applied to the cone pulley, and the table is rotated slowly by the gears and cone

pulley and their supporting members. Then if the former carries the pipe around in a curved line concentric to its axial center for a half of a full revolution, and if the machine is stopped after making a half of a revolution, a semi-circular bend is formed, as shown in Figs. 8 and 9, but if it is carried around to substantially a full revolution, a full circular curve is formed in the pipe.

- 10 The abutment roller can be moved to engage the sides of pipes that are placed on the extension 12, and secured by the mandrel and its rod off to one side of the tangential line B. This is done by moving the plate 15 20, to the desired point, and clamping it in place, and is used where a curved portion is wanted in the pipe and one or both of the ends of the pipe are required to stand at a certain angle to each other, or where one 20 end is required to stand at a certain angle to the curve itself.

I find in practice that where complete circular coils of pipe are required, it is best, when they are made of pipe of about from 25 two inches up to six inches in diameter, that the pipe be made into semi-circular coils and then that their ends be secured together by any suitable means. I preferably use the flanged clamping means shown in 30 Fig. 12.

A number of half circular coils can be secured together in this manner, and by raising them so as to pull them apart, a full circular spiral coil is obtained from the flat 35 semi-circular coils formed on my machine.

I find in practice that with large thick pipes it is an advantage to have the former rotate its pipe abutment roller 18, so that the pipe gripping groove of this driver roller 40 45 50 55 60 65 70 75 the end of the pipe is clamped to the projection; means for rotating the former, and an adjustable abutment roller for preventing outward movement of the unbent portion of the pipe.

4. In a pipe bending machine, the combination of a former comprising a semi-circular gear having an extension on one end, a gear of less diameter than the semi-circular gear and in mesh therewith, said gears having portions provided with registering grooves adapted to receive a pipe to be bent; a U-shaped clamp, one end of which is adapted to be inserted in the forward end 15 of the pipe and is formed with annular knife-edged pipe gripping elements, the other end extending behind said extension and is provided with a bolt which is adapted to be screwed against said extension, thereby 20 to clamp the end of the pipe thereto, a circular table to which said former is bolted, means for rotating said table, and an adjustable abutment roller for preventing outward movement of the unbent portion of the 25 pipe.

5. In a pipe bending machine, the combination with a former comprising a semi-circular gear, a gear of less diameter than the semi-circular gear and in mesh therewith, said gears having portions provided with registering grooves adapted to receive a pipe to be bent, of a longitudinally adjustable mandrel adapted to be inserted in said pipe, the forward end of which extends 30 to the bending point of the pipe between the two gears, an extension on the end of the semi-circular gear next the forward end of the pipe, and means for securing the for- 35

ward end of the pipe to said projection, a circular table to which said semi-circular gear is screwed, means for rotating said table, and an abutment roller at a point coincident with the rear portion of the mandrel, for preventing outward movement of the unbent portion of said pipe.

6. In a pipe bending machine, a table, a circular plate in the surface of said table, and gearing for rotating the same, a half round former secured to said plate, having gear teeth thereon, an adjustable bearing on 40 said table, a gear mounted in said bearing and in mesh with said former, said former and said gear having portions provided with registering grooves to receive a pipe to be bent, an extension on the end of the former 45 next the gear, and means for clamping the end of a pipe inserted between said former and gear, to said extension, a mandrel inserted in said pipe, a rod secured to the rear end of said mandrel, an adjustable block on 50 said table to which the free end of said rod is adjustably secured, the forward end of said mandrel being rounded and extending slightly beyond the bending point of the pipe, and an adjustable bearing on said 55 table, and an abutment roller mounted in said bearing and engaging said pipe at a point coincident with the rear portion of the mandrel, to prevent outward movement of the pipe while being bent.

In testimony whereof I affix my signature in presence of two witnesses.

HOMER P. CURTIS.

Witnesses:

R. B. McCONNELL,
R. E. APPLEQUIST.
